US00D975034S

(12) **United States Design Patent** (10) Patent No.: **US D975,034 S**
Greiser et al. (45) Date of Patent: ** Jan. 10, 2023

(54) **EQUIPMENT FOR DISTRIBUTION OF ELECTRIC POWER**

(71) Applicant: **Beckhoff Automation GmbH**, Verl (DE)

(72) Inventors: **Frank Greiser**, Rheda-Wiedenbrück (DE); **Hans Beckhoff**, Verl (DE)

(**) Term: **15 Years**

(21) Appl. No.: **35/515,093**

(22) Filed: **May 18, 2022**

(80) **Hague Agreement Data**

Int. Filing Date: **May 18, 2022**

Int. Reg. No.: **DM/223148**

Int. Reg. Date: **May 18, 2022**

Int. Reg. Pub. Date: **Sep. 9, 2022**

Primary Examiner — Michael A. Pratt

(57) **CLAIM**

The ornamental design for the equipment for distribution of electric power, as shown and described.

DESCRIPTION

1. Equipment for distribution of electric power

1.1 : Perspective top view

1.2 : Perspective rear view

1.3 : Right

1.4 : Front

1.5 : Back

1.6 : Top

1.7 : Rear view

1.8 : Left

1.1: Perspective top view of a function module of a modular equipment for distribution of electric power and data signals; 1.2: Perspective rear view of the function module; 1.3: Right view of the function module; 1.4: Front view of the function module; 1.5: Back view of the function module; 1.6: Top view of the function module; 1.7: Rear view of the function module; 1.8: Left view of the function module; the function module can be plugged onto a baseplate of a modular equipment for distribution of electric power and data signals as a rear panel and then screwed in place using captive screws located in the baseplate.
